[57] **CLAIM**

The ornamental design for an electric ambient air breathing pump, as shown and described.

DESCRIPTION

FIG. 1 is a top plan view of an electric ambient air breathing pump showing my new design;

FIG. 2 is a rear elevational view thereof;

FIG. 3 is a left side elevational view thereof;

FIG. 4 is a right side elevational view thereof;

FIG. 5 is a front elevational view thereof; and

FIG. 6 is a bottom plan view thereof.
